UNITED STATES PATENT OFFICE.

GEORGE M. COBURN, OF WALTHAM, MASSACHUSETTS.

UPRIGHT DRILL.

SPECIFICATION forming part of Letters Patent No. 245,134, dated August 2, 1881.

Application filed October 4, 1880. (Model.)

To all whom it may concern:

Be it known that I, GEORGE M. COBURN, a resident of Waltham, in the county of Middlesex and State of Massachusetts, have invented 5 certain new and useful Improvements in Upright Drills; and I do hereby declare that the following is a full, clear, and exact description thereof, reference being had to the accompanying drawings, and to the letters of reference 10 marked thereon, making a part of this specification.

This invention relates to hand-drilling machines adapted to produce automatically a fast or slow motion of the drill at the pleasure of 15 the operator.

It has for its object an improvement in the means, first, for producing a slow automatic feed of the drill and for its adjustment; second, for throwing the drill out of gear automatically, and for producing its quick return when it has completed its downward movement; third, for changing the speed and power of the drill; fourth, for lifting the drill-table out of way of the foot-piece by a hinged joint; 25 and, fifth, for adjusting the foot-piece and table at different heights.

Figure 1 in the accompanying drawings is a front elevation, showing the drill-table thrown up upon its hinge; Fig. 2, a central transverse section taken laterally through the drill in line $x x$, Fig. 4; Fig. 3, a side elevation, with the side gearing removed to illustrate the parts otherwise hidden thereby, and showing the drill-table in working position; and Fig. 4 is 35 a top view of the apparatus.

A, Figs. 3 and 4, represents the main upright frame of the machine; B, the spindle of the drill, supported by the frame in vertical bearings $a a$; A', Figs. 1 and 2, a horizontal side frame projecting from and connected with the main frame A and supporting the bearings for the horizontal shafts C E F. The driving-shaft C is geared by means of the intermediate bevel-wheels directly to the spindle B, and may be driven directly from the actuating-crank D of the machine, or indirectly and with a higher speed by means of a secondary set of gear-wheels and an auxiliary speed-shaft, E. A fly-wheel shaft, F, is geared to the shaft E, and also to crank-head D', so as to have constant motion. The crank D is secured to

a head or sleeve, D', carrying upon its inner end a gear-wheel, 1. This head or sleeve is left free to revolve loosely upon the end of the driving-shaft C, but may be rigidly fixed to it 55 by means of a set-screw, e. (See Figs. 2 and 4.) The gear-wheel maintains the same position upon the crank-head D' whether the latter is fixed or loose, and it meshes with a smaller pinion upon the end of the second horizontal 60 shaft, E. (See Fig. 4.) A larger gear-wheel, 2, is secured by a feather on this shaft E, so as to revolve with it and yet be free to move longitudinally in and out of gear with a smaller gear-wheel, 3, upon the front shaft, C, (see Figs. 65 1 and 2,) and it meshes also constantly with a small extended pinion, 4, (see Fig. 4,) upon the shaft of the fly-wheel F. When it is desired to increase the speed of the main shaft C the crank-head D' is loosened, so as to turn freely 70 with its gear-wheel 1 upon the end of the shaft. The movement of the crank is then communicated by means of the gear-wheel 1 to the second shaft, E, and from it, by means of the gear-wheel 2, to the pinion 3 upon the shaft C, the 75 difference in diameters of the gear-wheels serving to multiply greatly the speed. Where a slow speed is required the crank-head D' is firmly secured to the shaft C by means of the set-screw e, and the pinion 2 upon the speed- 80 shaft E is thrown out of gear with the pinion 3, so that the movement of the crank is imparted directly to the main shaft C. In either case the movement of the crank through the intervention of the gear-wheels 1, 2, and 4 is 85 constantly communicated to the fly-wheel shaft F without change, so that the fly-wheel will always revolve in the same direction and with uniform speed, whether the speed-shaft E be in or out of gear with the shaft C, and consequently revolving with slow or with rapid motion. The revolution of the shaft C produces, by means of beveled gears G G', Figs. 1 and 2, a constant revolution of the drill-spindle B. Upon the upper end of the spindle is placed a 90 horizontal ratchet-wheel, H, (see Fig. 4,) which turns loosely upon the spindle.

Upon a frame or plate, K, supported over the wheel H by means of a curved bracket, L, secured to the upper part of the frame A, are 95 pivoted two levers, M M, whose outer arms extend to the outer edge of the ratchet-wheel H

and carry swinging pawls *m m* to engage the ratchet-teeth of the wheel, and whose inner arms are fitted with friction-rollers *n n* to bear against a cam, *o*, secured to the spindle *B*. The 5 inner ends of the levers *m m* are thrown inward so as to bring the friction-rollers into constant bearing against the cam by means of suitable springs *p p*, Fig. 4. The levers are so adjusted with reference to the cam that the 10 revolution of the spindle will alternately throw the inner ends of the ratchet-levers outward and their outer arms forward, and thereby produce, by means of the engagement of the pawls *m m* with the ratchet-wheel teeth, a corresponding 15 movement of the ratchet-wheel. The forward movement of each lever under the influence of the cam will compress the lever-spring, which will then operate to throw back the lever when the pressure of the cam is removed. The alternate movement of the two 20 levers will produce a nearly constant movement of the ratchet-wheel. The extent of the forward movement or throw of each lever, and consequently the degree of movement of the 25 ratchet-wheel at each revolution of the drill spindle and cam, is regulated by means of the bar *P* pivoted upon the spindle and supported upon a pillar, *P'*, Fig. 3, projecting from the bracket *L*. The position of this bar *P* is adjusted 30 by means of a set-screw, *c*, passing through a slot in the bar. A pin or stop, *d*, depends from this bar in front of the outer end of each arm and serves to arrest the backward movement of the arm under the influence of 35 its spring. By turning the bar *P* so as to bring the stops nearer to or farther from the levers and securing it when adjusted by means of the set-screw *c* the throw of each lever is controlled so as to produce a slower or more rapid movement 40 of the ratchet-wheel.

The spindle *B* is fitted below the feed-wheel *H* with an exteriorly-threaded sleeve, *J'*, which is so made to engage the spindle as to prevent any independent longitudinal movement of the 45 sleeve and spindle, and yet allow the spindle to revolve freely within the sleeve. The feed of the spindle *B* is produced by means of this threaded sleeve *J'* and an interiorly-threaded nut, *J*, (see Fig. 2,) fitted thereon. This feed-nut *J* is free to revolve in bearings in the frame 50 *A* and carries at its upper end a loose clutch, *R*, Figs. 1 and 2, which when thrown up engages co-acting projections on the under side of the horizontal ratchet-wheel *H*. When the 55 clutch *R* is slipped up to engage the ratchet feed-wheel *H* the movement of the ratchet-wheel is transmitted to the nut, and the latter by its rotation causes downward vertical movement in the drill-spindle *B*. The feed-nut *J* is coupled 60 by bevel-gears 5 and 6 with the shaft of a hand-wheel, *S*, revolving horizontally in a bracket, *S'*, extended for the purpose from the main frame *A*. A cog-wheel, 7, formed upon a collar sliding longitudinally upon the spindle *B* above 65 the lower drive bevel-wheel *G*, and made to rotate with the spindle by means of a spline between the two, engages the bevel-wheel 6

when properly carried up against it. (See Fig. 2.)

The lower end of the collar of the wheel 7 is 70 provided with a clutch, to engage the face of the lower drive-wheel, *G*, when dropped against it. A forked clutch-bar, *R''*, Figs. 1 and 2, engages the collar of the wheel 7, and is connected with the upper clutch-bar, *R'*, by a 75 coupling-bar, *T*, sliding in suitable ways, or upon pins projecting from the fixed bearings *a a* of the spindle, so that when the upper clutch, *R*, engages the ratchet-wheel *H* the lower clutch shall be disengaged from the 80 lower drive-wheel, *G*, and vice versa. A pin mounted upon the threaded sleeve *J'* projects through a longitudinal slot in said reversing slide-bar *T*, and an adjustable stop is fitted in the slot, against which the pin is brought to 85 bear in the upward movement of the drill-spindle *B* when it has nearly reached its highest desired elevation, so that spindle *B* will carry up with it the reversing-bar *T*. This movement of the bar will operate to engage 90 the upper and disengage the lower clutch, and thus reverse the feed of the spindle. In its downward movement the pin from the sleeve *J* will bear against a lower stop in the slot of the bar *T*, so that when the drill has nearly 95 reached its lowest point the reversing bar *T* will be forced down, the upper clutch disengaged, and the lower clutch made to engage the bevel drive-wheel *G*, so as to reverse the feed automatically and produce a fast upward 100 movement of the drill.

When the drill is being fed by the ratchet-wheel *H* it may be fed independently as fast as desired by means of the hand-wheel *S*. The feed of the drill may be placed wholly under control of the hand-wheel *S* by throwing up the pawls *m* from the ratchet-wheel and sliding up the reversing slide-bar *T* to disengage the lower clutch from the drive-wheel. When this clutch is not released from its connection with the driving-wheel the feed will be automatically reversed, producing alternately, with a constant movement of the crank and rotation of the drill in one direction, a slow downward and a rapid upward feed of 115 the drill-spindle.

The foot-piece *U* of the drill is fitted to a vertical post, *W*, of the main frame by means of a collar encircling said post. A series of circumferential grooves, *t t*, are cut upon the 120 post at regular intervals, and a catch, *x*, Fig. 3, upon the under side of the foot-piece is arranged to engage said grooves, and thus support the foot-piece at the height of either of said grooves, and yet permit it to turn upon 125 the post without slipping.

A suitable table, *Y*, is hinged to a collar, *Z*, fitted upon the post above the foot-piece so as to be supported by said foot-piece. The table may be turned up upon its hinge against the 130 post out of the way of the foot-piece, so that the latter may be used alone, or the table may be let down upon the foot-piece, in which case it receives lateral support therefrom by means

of a projection upon its under side made to fit closely into the recess or fork provided in the front of the foot-piece to facilitate the drilling of tires, &c., thereon.

- 5 In the operation of this improved drilling-machine the fly-wheel has a constant motion faster than that of the driving-shaft, produced by means of the intermediate spur-gearing, and this motion is continuous and uniform in the 10 same direction, independent of the changes which may be made in the speed of the drill-spindle, by throwing the speed-shaft in or out of gear with the main shaft. A change of speed in the drill-spindle B, without changing 15 the speed of the driving-crank, is readily effected by loosening or tightening the attachment of the hub D' of the crank to the main driving-shaft C, and throwing the auxiliary speed-shaft E in or out of gear with said main shaft C.
- 20 The feed of the drill may be produced with a uniform gradual movement by sliding up the reversing-bar T so as to leave the gear-wheel 7 disengaged from the drive-wheel G, and thus cause the feed-nut J to be operated by the 25 ratchet-wheel H, actuated by the cam and levers on the upper end of the spindle B, this ratchet-feed being rendered slow or fast by changing the position of the bar P, which controls the throw of the levers. A rapid return 30 of the drill-spindle B will be produced automatically by the movement of the reversing-bar T, through its connection with the threaded sleeve J' on the drill-spindle, which will operate so soon as the drill-spindle has reached its 35 lowest point to disconnect the feed-nut J from the ratchet-wheel H and connect it by means of the gearing 5, 6, and 7 with the main shaft, so as to produce a rapid reverse movement of the feed-nut J. This reverse movement will, 40 in turn, be automatically checked by the automatic movement of the reversing-slide T, actuated by the upward movement of the threaded sleeve J', which will operate to disconnect the gear 7 from the driving-wheel G, and to connect nut J again with the feed-wheel H.
- 45

What I claim as new, and desire to secure by Letters Patent, is—

1. The combination, with the driving-shaft C, of the drill and with an auxiliary shaft, E, provided with a sliding pinion, by means of 50 which it may be thrown in and out of gear with said driving-shaft C, of a crank-hub, D', and attached pinion 1, fitted to turn loosely upon the end of the driving-shaft C, and to gear with a pinion upon the auxiliary shaft E, 55 and be secured at will to said driving-shaft C by means of a set-screw, substantially in the manner and for the purpose herein set forth.

2. The combination of the crank-hub D' and pinion 1, the auxiliary shaft E, and fly-wheel 60 shaft F, geared to move together, with the driving-shaft C arranged to be connected to and driven by either the crank-hub D' or the auxiliary shaft E, as may be desired, substantially in the manner and for the purpose herein set forth.

3. The combination of the upper clutch, R', the feed-nut J, the ratchet-wheel H, sliding bar T, threaded sleeve J', reversing-pin, and lower clutch, R'', substantially as and for the 70 purpose herein set forth.

4. The combination of the bevel-gearing 5, 6, and 7, the feed-nut J, the driving-shaft C, and bevel-gear G G', substantially as and for the purpose herein set forth.

5. The combination, with the main post W of an upright drilling-machine, and with a collar, Z, traversing and rotating upon said post, of a plate or table, Y, hinged to said collar to admit of being thrown up vertically against 80 the post, substantially as and for the purpose herein set forth.

In testimony whereof I have signed my name to this specification in the presence of two subscribing witnesses.

GEO. M. COBURN.
